UNITED STATES PATENT OFFICE.

WILLIAM A. BOLE, EDWIN RUUD, AND EDWARD S. McCLELLAND, OF PITTSBURG, PENNSYLVANIA.

DESIGN FOR A GAS-ENGINE FRAME.

SPECIFICATION forming part of Design No. 29,800, dated December 13, 1898.

Application filed August 24, 1897. Serial No. 649,397. Term of patent 14 years.

To all whom it may concern:

Be it known that we, WILLIAM A. BOLE, EDWIN RUUD, and EDWARD S. McCLELLAND, citizens of the United States, residing at Pittsburgh, in the county of Allegheny and State of Pennsylvania, have invented and produced a new and original Design for a Gas-Engine Frame, of which the following is a specification.

Our invention relates to a new and original design for a gas-engine frame.

In the accompanying drawings, illustrating our invention, Figure 1 is a perspective view showing the external appearance or configuration of a gas-engine frame embodying our design; Fig. 2, a front elevation, and Fig. 3 an elevation on a plane at right angles to that of Fig. 2.

The leading characteristic feature of our design is the symmetrical, graceful, and distinctive appearance due to the external formation or configuration of two similar vertical cylinders 1 mounted on a closed crank-case 2, with each cylinder surrounded for a portion of its length by a jacket 3. The jackets 3 have the appearance of cylinders of greater diameter than the cylinders 1 and of being placed on and above the cylinders 1. Each jacket extends from the top or head 25 downward a portion only of the length of the cylinder 1 and not down to the crank-case, so that the cylinders 1 are clearly seen between the jacket and the crank-case. The cylinders 1 are also accompanied by symmetrically-disposed projecting portions 4, which extend laterally from a casing 5, are turned

upward at their outer ends, and terminate at the top of the jackets 3. The parts 6 and 7 represent gear-casing and are fixedly connected with the casing 5 by means of a supporting-frame 8. The casing 5 is located between the jackets 3. Beneath this casing and rising from the lower casing 2 is a central governor-standard 9, occupying the space between the cylinders 1. The upper portion of 45 this standard is reduced in size and is in contact with the casing 5, and it is provided about midway of its length with a shoulder 10 and a collar 11. The lower casing 2 is provided with a bonnet or door 12 on what may be called the 50 "front" of the case and which forms a modifying feature affecting the general appearance and configuration of the design.

Referring to Figs. 1 and 2, it will be seen that the casing 2 is also provided at opposite 55 sides with circular plates 13, from the center of which project bosses 14, which have on their surface ribs 15, connecting with the plates 13. These features also add to the distinctive configurative features of the engine. 60

We claim as our invention and desire to secure by Letters Patent—

The design for a gas-engine frame, substantially as shown and described.

In testimony whereof we have hereunto set 65 our hands.

WILLIAM A. BOLE.
EDWIN RUUD.
EDWARD S. McCLELLAND.
